KNOCKDOWN WALL FIXTURE

Marriott T. Johnston, Chicago, Ill., assignor to
Walgreen Co., Chicago, Ill., a corporation of
Illinois

Application May 5, 1932, Serial No. 609,532

9 Claims. (Cl. 211—148)

This invention relates to fixtures and more particularly to sectional wall structures of the shelf type, although certain features thereof may be employed with equal advantage for other purposes.

It contemplates more especially the provision of complementary sections capable of ready association and disassociation to provide a wall fixture of variable dimensions and extent. Wall attached shelves and other fixtures are generally employed as necessary equipment in retail merchandising stores. Varied merchandise is handled in retail enterprises and suitable facilities for their ready accessible storage must be provided. Known wall fixtures have not proven entirely satisfactory from the installation and removal standpoint, since these are usually built to meet the special requirements of particular stores for permanent attachment to the walls thereof. Stores vary in size and layouts so that it proves very difficult to adapt a standard wall-shelf structure for different situations and stores owing to the great variation in the dimensional extent and requirements of different types of merchandise. Special wall-shelves and cabinets are exceedingly expensive, and prove more or less valueless should there be a necessity for dismantling or effecting the removal thereof for use in other stores, situations or locations, requiring fixtures of different dimensional extent and characteristics.

This has proven very expensive in chain store operations, since there is often a requirement for changing location or stores so that the removal of fixtures from one for utilization in another would be possible and involve nothing other than nominal moving and installation expense. Then, too, the cost of standard units manufactured on a production basis is considerably less than building wall fixtures of special design and dimensional extent for different situations. Standardization in wall fixtures to enable interchangeability and the extension thereof by duplication of units or addition of similar units for end-alignment is of substantial significance and importance to economically meet modern commercial requirements in retail stores.

One object of the present invention is to simplify the construction and improve the usefulness of fixtures of the character mentioned.

Another object is to provide novel sectional wall-shelf units capable of ready assembly into fixtures of varying size and dimensional extent.

Still another object is to provide novel, simple and inexpensive means for maintaining complementary elements in assembled relation to define wall-shelf units of variable extent.

A further object is to provide standard shelf units of novel construction entailing minimum installation and dismantling expense.

A still further object is to provide complementary wall-shelf elements capable of ready as-

sembly into fixtures for varied merchandise facilities.

Still a further object is the provision of standard wall-shelf units capable of ready assembly and dismantling to enable the use thereof for different situations and store locations to meet varying requirements from time to time.

Other objects and advantages will appear from the following description of the illustrative embodiment of the present invention.

In the drawings:

Figure 1 is a front view in elevation of a fixture embodying features of the present invention, parts thereof being broken away to clarify the showing.

Figure 2 is a sectional view taken substantially along line II—II of Figure 1.

Figure 3 is a sectional view taken substantially along line III—III of Figure 1, it being shown with a break therebetween to represent the intermediate portion not capable of convenient showing in the drawings.

Figure 4 is a view taken substantially along line IV—IV of Figure 3.

Figure 5 is a view taken substantially along line V—V of Figure 3.

Figure 6 is a sectional view taken substantially along line VI—VI of Figures 2 and 3.

Figure 7 is a sectional view taken substantially along line VII—VII of Figure 1.

Figure 8 is a sectional view taken substantially along line VIII—VIII of Figure 1.

Figure 9 is a perspective view of a wall bracket utilized to detachably join the fixture to a vertical surface against accidental movement relative thereto.

The structure selected for illustration comprises a plurality of vertical members 10 preferably though not essentially constructed from wood to present upstanding shelf-supports. The vertical supports 10 are substantially of rectangular configuration and sized to correspond with the height and depth of the desired fixture structure. This may vary within a wide range, and depends entirely upon the dictates of commercial practice and the requirements of any particular enterprise. In fact, the vertical supports 10 may be composed of a plurality of segmental units of multitudinal depth so as to enable the variation in the resulting wall-shelf structure without substitution or the necessity of carrying in stock supports 10 of varying depth.

Any number of supports 10 may be equi-distantly disposed upon a base 11 which has a chambered interior 12 to reduce the weight of the structure. In order to enable the detachable connection of the vertical supports 10 to the base 11, the top surface 13 thereof and the contacting support edges are provided with complementary interengaging means. The interengaging means

comprises, in this instance, a U-shaped plate 14 which is sized to telescopically receive the lower edge region 15 of the vertical supports 10. Suitable screw fasteners 16 project through the sides 5 of the plate 14 for effecting the attachment thereof to the vertical supports. In the present embodiment, the top region 17 of the vertical supports 10 are also provided with edge engaging plates 18 corresponding in size and configuration 10 with the lower edge plate 14. Fasteners 19 extend through the sides thereof for attachment to the top edge region 17, thereby serving as a reinforced metallic edge thereof. Rivets 20 project through apertures formed in the edge of the 15 plate members 14 and 18, and the button heads 21 thereof project in cavities 22 provided in the body of the supports 10 through the end regions 15 and 17 thereof to freely accommodate the rivet heads 21. Dished washers 23 are axially 20 apertured for telescopic reception by the rivets 20, and these are normally urged in the direction of the head 21 by virtue of spiral springs 24 which envelope the rivets 20. The springs 24 abut against a washer 25 which is retained upon 25 the rivet shank 20 by swaging the extremity thereof into a deformed flat projection 26 which extends beyond the apertures of the washer 25 to serve as a retaining member therefor. In consequence thereof, the dished washer 23 will 30 be normally urged in the direction of the button-head 21, and such serves to effect the ready attachment and detachment of the vertical supports 10 to adjacent surfaces which have complementary engaging means which are permanently set and for that reason do not require any 35 adjustment, manipulation, tightening or loosening to effect assembly or dismantling. The adjacent surfaces adapted for contact with the supports 10, are provided with flat plate members 27 having keyhole-shaped apertures 28 provided 40 therein to accommodate the dished washer 23 as will appear more fully hereinafter.

The larger portion 29 of the aperture 28 accommodates the dished washer 23, and this 45 merges in a smaller portion which is only large enough to accommodate the rivet shank 20. In consequence thereof, the dished washer 23 is axially projected through the larger portion 29 of the keyhole-shaped apertures 28 and thence disposed toward the smaller portion 30 thereof to effect the retention by contact of the dished washer 23 with the side thereof obverse from the side of original entry. It is apparent, therefore, that a connection is established against the edge 50 of the spring 24 which establishes sufficient frictional engagement with the contacting surfaces to preclude accidental removal by displacement in a direction opposite to that just described.

The plate 27 is attached to the top surface 13 60 of the base 11 in a direct transverse line thereto so to effect the detachable joinder of the vertical support 10 therewith. Any number of attaching expedients, in this instance two, are provided in the plate members 27, and these are 65 provided with corner apertures 31 therein for receiving screw fasteners to effect their permanent attachment. The base member 11 is provided with suitable notches or cavities 32 in communication with the keyhole-shaped apertures 28 provided in the plates 27 so as to afford 70 the entry of the fastener 29 with their auxiliary elements 23 thereon. A plate 34 apertured and shaped similarly to the plate 27 is provided on the bottom surface of a top member 35 which 75 rests on the vertical supports 10. The top mem-

ber 35 has a plate 34 attached thereto by narrow fastener screws projecting through the apertures 36 therein, and the position of the keyhole-shaped apertures 37 thereof extends in a direction directly opposite to the apertures 28 in the bottom plates 27 which are in confronting alignment therewith. Consequently, the vertical supports 10 are first caused to register with the apertures 28 in the lower plate 27 displacement relative thereto to effect the detachable engagement therewith against the urge of the spring 24, and thereupon the top member 35 is shifted to its operative position for registry with the aperture 37 in the top plate 34. This enables the substitution of any of the vertical supports 10 by simply removing the top members 35 from assembled position. The top members 35 have a suitable cavity 38 provided therein for communication with the apertures 37 in the plate 34, thereby accommodating the rivet 20 with its attaching expedient 23 for lodgement therein to effect the detachable joinder therewith.

In order that any number of vertical supports 10 may be provided for predetermined spaced relation in parallelism, the base 11 and top members 35 are sectional for affording end-alignment of any number of multiple sections. To this end, the top member 35 is chambered as at 39 similarly to the chamber 12 provided in the base 11 so as to define adjacent walls 40 which are 30 sufficiently restricted in dimensional thickness to afford the projection of a carriage bolt 41 therebetween to effect their detachable connection. The carriage bolts 41 are accessible through the open bottoms and tops 42 of the base members 11 and 35, respectively. The wall fixture may, therefore, be extended for any desired distance by the end-alignment of multiple sections to meet the requirements of any particular installation. It is worthy of note that when the cavities 32 and 38 of both the bottom and top members 11 and 35, serve to afford attachment of a vertical member 10 that comprises a part of adjacent sections or units, one half of the cavities 32 and 38 are formed in the adjacent ends of the bottom and top members 11 and 35 with their plates 13 and 34 attached thereover.

Now, then, a plurality of horizontal shelves 43 are extended between the vertical supports 10 which serve as partition members, and the shelves 43 are supported by means of brackets or other suitable expedients such as strips of wood 45 disposed in horizontal alignment for attachment to the confronting walls of the vertical supports or partition members 10 by means of screw fasteners 46. Any number of shelves 43 may be disposed between the vertical supports 10, and this depends largely upon the extent thereof and the desired spacing to meet the requirements of any particular merchandise or as commercial 50 practice may dictate more practical for universal requirements. The shelves 43 correspond in depth with the vertical supports 10, and these rest upon the strips 45 which serve as a shoulder support.

The shelves 43 are retained against accidental 55 forward removal by means of facing strips 47 which are detachably secured to the front edges of the vertical supports 10. To this end, the facing strips 47 are provided with plates 48 attached to the surface thereof by means of suitable fasteners 49. The plates 48 have normally 60 projecting clips 50 formed thereon to present a depending tongue 51 adapted to engage a plate 52 anchored to the adjacent surface of the vertical supports 10 by means of fasteners 53. It 65

is to be noted that the plate 52 is provided with a vertical slot 54 which freely receives the clip 50 therethrough so that the tongue 51 thereof will engage the bottom edge of the slot 54 to preclude removal in its downwardly displaced and attached position. Vertically upward displacement of the facing strips 47 will cause the tongue 51 to disengage the plate 52 so as to afford the removal thereof through the slot 54, thereby allowing the disengagement of the facing strips 47 from the forward edges of the partitions or vertical supports 10. The forward edges of the vertical supports 10 are provided with cavities 55 in the region of the slot 54 for communication therewith so as to accommodate and receive the clip 50 with its tongue 51 therein. Any number of interengaging plates 48 and 52 may be provided along the forward edges of the vertical supports 10, and the facing strips 47 are sufficiently wide to project beyond the forward edges of the vertical supports 10 to retain the shelves 43 against displacement in the direction thereof.

The vertical facing or finishing strips 47 may be interrupted in length so as to afford the provision of one or more horizontal ledges 56 projecting beyond the forward limits thereof to serve as a rest for additional commodities or equipment as may be desired or required in any particular enterprise. The ledge 56 constitutes an extension of any selected shelf 43 positioned at a convenient elevation from the base 11 for general accessibility, there being a complementary joint 51 formed on the adjacent edges of the shelves 43 which is in alignment with the ledge 56 to assist in the support thereof. Corner brackets 58 formed from wood or other material are disposed beneath the ledge 56 in alignment with the vertical supports 10 for attachment thereto and the under side of the ledge 56 by means of suitable fasteners 59, thereby effectively supporting the ledge 56 along the entire extent thereof, it corresponding in length to the base 11 and top member 35. The facing or finishing strips 47 disposed beneath the ledge 56 are preferably provided with a notch 60 to accommodate the ledge supporting blocks 58, and it is apparent that the finishing strips 47 serve to conceal the shelf supporting strips 45 from view. The entire units or assembled structure is detachably connected to the wall 61 of a store by means of plates 62 which have confronting tangs 63 stamped therefrom to assume a normal parallel position at spaced intervals corresponding and in registry with the vertical supports 10. The tangs 63 are preferably though not essentially stamped from wall securing plates 62 and the top thereof is commensurate with the width of the vertical supports 10 to receive the rearward edges thereof.

The tangs 63 are provided with apertures 64 so that screw fasteners may be projected therethrough for anchoring attachment to the lateral walls of the vertical supports 10. In consequence thereof, the entire structure is fastened to the wall through the medium of the plates 62 which have apertures 65 provided therethrough at spaced intervals to effect the attachment thereof to the wall 61. Any number of wall strips 62 may be employed, but in the present embodiment there are two in vertical spaced relation intermediate the base 11 and top 35.

It is to be noted that the shelves 43 may be removed in any particular section of the structure, and a closed cabinet 66 provided in a section defined by confronting vertical supports and

the horizontal surfaces determined by the base 11 and/or top member 35 in conjunction with any particular shelf 43 which may serve as a support therefor. The cabinet 66 is a self-contained unit and sized in this particular embodiment to utilize the section defined between two vertical supports 10, the bottoms of the top member 35, and the shelf 43 which is in alignment with the ledge 56. Any additional self-contained units may be substituted for the shelves 43, and these may vary within a wide range depending upon the individual requirements of particular merchandising enterprises. For instance, cigarettes are better stored in closed cabinets 66 preferably provided with transparent doors 67 to keep such commodity within public view.

With the arrangement of parts above described, it is apparent that a wall-shelf structure of variable size has been provided merely by substituting or end-aligning multiple units. These may be assembled to meet the requirements of any particular dimensional area or store, thereby availing the use of the same units for different stores should it be necessary to change locations or expand to meet enlarged requirements from time to time. The production of standard component elements and/or units of the character described is far less expensive than the cost of specially constructed fixtures, and the assembly thereof entails far less time and labor. This coupled by the fact that fixtures of this type may be readily dismantled for further use in different stores renders such especially advantageous for commercial enterprises.

Various changes may be made in the embodiment of the invention herein specifically described without departing from or sacrificing any of the advantages of the invention as defined in the appended claims.

I claim:

1. In a sectional wall fixture, the combination with vertical support members, top and bottom members detachably applied to the extremities of said vertical members, sustaining means for shelf members on said vertical support members, horizontal shelf members removably supported by said sustaining means between said vertical members, the end vertical support members being attached to said top and bottom members so that the vertical median line of the former are in alignment with the edges of the latter to enable the association of wall fixture sections without vertical member duplication, and inter-engaging means detachably connecting said vertical support members with said top and bottom members to retain the assembly thereof as a rigid unit.

2. In a sectional wall fixture, the combination with vertical support members, top and bottom members detachably applied to the extremities of said vertical members, sustaining means for shelf members on said vertical support members, horizontal shelf members removably supported by said sustaining means between said vertical members, permanently set inter-engaging means detachably connecting said vertical support members with said top and bottom members to retain the assembly thereof as a rigid unit, the end vertical support members being attached to said top and bottom members so that the vertical median line of the former are in alignment with the edges of the latter to enable the association of wall fixture sections without vertical member duplication, vertical finishing strips applied to the exposed edges of said support members, and per-

manently set fasteners on said finishing strips for establishing detachable connection to the exposed edges of said vertical supports.

3. In a sectional wall fixture, the combination with vertical support members, top and bottom members detachably applied to the extremities of said vertical members, sustaining means for shelf members on said vertical support members, horizontal shelf members removably supported by said sustaining means between said vertical members, permanently set inter-engaging means detachably connecting said vertical support members with said top and bottom members to retain the assembly thereof as a rigid unit, the end vertical support members being attached to said top and bottom members so that the vertical median line of the former are in alignment with the edges of the latter to enable the association of wall fixture sections without vertical member duplication, vertical finishing strips, permanently set fasteners detachably connecting said finishing strips to the exposed edges of said vertical supports, and wall strip engaging brackets detachably secured to said vertical supports.

25 4. In a wall fixture, the combination with vertical support members, top and bottom members detachably applied to the extremities of said vertical members, sustaining means for shelf members on said vertical support members, horizontal shelf members removably supported by said sustaining means between said vertical members, permanently set spring actuated, inter-engaging means detachably connecting said vertical support members with said top and bottom members to retain the assembly thereof as a rigid unit, the end vertical support members being attached to said top and bottom members so that the vertical median line of the former are in alignment with the edges of the latter to enable the association of wall fixture sections without vertical member duplication, finishing strips, permanently set co-operating means on said finishing strips and vertical supports effecting detachable connection to the exposed edges of said vertical supports, wall strip engaging brackets detachably secured to said vertical supports, said top and bottom members being chambered, and means extending between said chambered members for detachably securing similar assembled units in end alignment.

50 5. In a wall fixture, the combination with vertical support members, top and bottom members detachably applied to the extremities of said vertical members, and inter-engaging means detachably connecting said vertical support members with said top and bottom members to retain the assembly thereof as a rigid unit, said inter-engaging means comprising plates having key-hole apertures therein attached to one of said members, and spring urged fasteners anchored in concealed association with the other of said members to project therefrom for adjustable registry with the apertures of said plates.

65 6. In a wall fixture, the combination with vertical support members, top and bottom members detachably applied to the extremities of said vertical members, brackets attached to the side walls of said vertical supports for supporting shelves thereon, horizontal shelf members removably supported between said vertical members, permanently set inter-engaging means detachably connecting said vertical support members with said top and bottom members to retain the assembly thereof as a rigid unit, the end vertical support members being attached to said

top and bottom members so that the vertical median line of the former are in alignment with the edges of the latter to enable the association of wall fixture sections without vertical member duplication, and vertical finishing strips having fasteners thereon for detachable connection to said vertical support members.

7. In a wall fixture, the combination with vertical support members, top and bottom members normally secured to the extremities of said vertical members, sustaining means for horizontal shelf members on said vertical support members, horizontal shelf members removably supported by said sustaining means between said vertical members, inter-engaging means for detachably connecting said vertical support members with said top and bottom members to retain the assembly thereof as a rigid unit, the end vertical support members being attached to said top and bottom members so that the vertical median line of the former are in alignment with the edges of the latter to enable the association of wall fixture sections without vertical member duplication, vertical finishing strips detachably connected to the exposed edges of said vertical supports, and permanently set inter-engaging means on said strips and adjacent vertical support members to enable their detachable engagement.

8. In a wall fixture, the combination with vertical support members, top and bottom members normally secured to the extremities of said vertical members sustaining means for horizontal shelf members on said vertical support members, horizontal shelf members removably supported by said sustaining means between said vertical members, permanently set inter-engaging means for detachably connecting said vertical support members with said top and bottom members to retain the assembly thereof as a rigid unit, the end vertical support members being attached to said top and bottom members so that the vertical median line of the former are in alignment with the edges of the latter to enable the association of wall fixture sections without vertical member duplication, vertical finishing strips detachably connected to the exposed edges of said vertical supports, and concealed inter-engaging means on said strips and adjacent vertical support members to enable their detachable engagement, said last named inter-engaging means comprising an apertured plate, and a tongue for removable registry with said plate aperture.

9. In a wall fixture, the combination with vertical support members, top and bottom members normally secured to the extremities of said vertical members, brackets attached to the side walls of said vertical supports for receiving shelves thereon, horizontal shelf members removably supported between said vertical members, permanently set inter-engaging means for detachably connecting said vertical support members with said top and bottom members to retain the assembly thereof as a rigid unit, the end vertical support members being attached to said top and bottom members so that the vertical median line of the former are in alignment with the edges of the latter to enable the association of wall fixture sections without vertical member duplication, and vertical finishing strips having fastening means for detachable connection to the exposed edges of said vertical supports.
